UNITED STATES PATENT OFFICE

2,168,414

RATE EXTENSION PUNCH

Clair D. Lake, Binghamton, N. Y., assignor to
International Business Machines Corporation,
New York, N. Y., a corporation of New York

Application December 28, 1937, Serial No. 182,058

16 Claims. (Cl. 164—113)

This invention relates to record card punching machines and more particularly to machines adapted to punch cards of the well-known Hollerith type.

5 The present invention is directed to the simplifying of punching a large number of record cards whereon a large number of the card columns are to receive perforations representing data peculiar to each individual card. Heretofore such data were punched by the laborious and time consuming method of manually punching each column of each card.

An object of the invention is to provide mechanical means controlled by a single manipulative means simultaneously to set up a plurality of values which may be read out step by step and punched in a plurality of card fields.

Another object of the invention is to provide a large number of value carrying elements each of 20 which elements is provided with a plurality of readable elements automatically to control a punching machine.

A further object is to provide a single manipulative means which automatically shifts the circuits from certain selected values from certain 25 columns to other columns.

Further objects of the instant invention reside in any novel feature of construction or operation or novel combination of parts present in the 30 embodiment of the invention described and shown in the accompanying drawings whether within or without the scope of the appended claims and irrespective of other specific statements as to the scope of the invention contained herein.

35 In the drawings:

Fig. 1 is a plan view of the reproducing punch and the rate extension keys.

Fig. 2 is a plan view of the reproducing punch.

40 Figs. 3 and 4 illustrate the card feed and interlock.

Fig. 5 is a view in side elevation of a portion of the punch mechanism, partly broken away to show some of the structure.

45 Fig. 6 is a sectional view through the punching mechanism.

Fig. 7 is a sectional view illustrating the brush shifting and controlling device.

Fig. 8 is a detail view showing the operation of the last column contacts by the card carriage.

50 Fig. 9 is the circuit diagram of the machine.

Fig. 10 is a view in front elevation (partly broken away) of the circuit selector mechanisms.

55 Fig. 11 is a sectional view taken longitudinally through the circuit selector looking toward the rear of the machine.

Fig. 12 is a sectional view taken on line 12—12 (Fig. 10) looking in the direction of the arrows.

Fig. 13 is a detail view of the key bar latches.

Fig. 14 is a sectional view taken on line 14—14 (Fig. 10) looking in the direction of the arrows.

Fig. 15 is a top plan view of the key locking mechanism.

Fig. 16 is a detail view showing the drive motor and the mechanism for lowering and raising the 10 selected value plate.

Fig. 17 is a plan view of the circuit selector contacts.

Fig. 18 is a detail view of the cam and cam arm for operating the value plate lowering and raising frame.

Fig. 19 illustrates one of the value plates.

Fig. 20 is a fragmentary sectional view taken on line 20—20 (Fig. 19).

Figs. 21 and 22 are detail views showing value plate tray locking and unlocking arrangement.

Fig. 23 illustrates a typical record card.

Fig. 24 illustrates the schedule of residential and commercial rates.

Fig. 25 is a diagrammatical view of the plug-board showing a typical plugging arrangement.

As stated above, the duplicating punch mechanism is substantially the same as that disclosed in the patent to Lee and Daly No. 1,976,618. To such a punch mechanism has been connected by a cable a circuit selector including a group of 30 selector keys 1 (Figs. 1 and 10).

The blank cards 3 are fed manually into the machine on a guide plate 4 and under a normally open card pressure plate 7 (Figs. 1, 2, 3 and 4). This plate is shown in its open position at 7' (Fig. 3).

When the card is in position the plate 7 is closed, whereupon a circuit (to be described later) is closed to bring into operation mechanism to feed the card to the punching position. This mechanism includes a picker knife 2 (Figs. 3 and 4) which at the proper time is moved toward the left. At the same time a card carriage 6 is moved to the right (Fig. 1) to a position to receive the card 3 when the picker 2 reaches the end of its leftward movement.

The card is then punched column by column according to the punch selector circuits set up, the carriage 6 moving to the left step by step. When the punching of the card is completed and the carriage 6 has reached the end of its leftward travel, the newly punched card 3 is automatically removed and the operation is completed.

The punches 5 (Fig. 6) may be operated normally by means of keys 9 or they may be controlled by a duplicator in accordance with the 45

50

55

perforations of a previously punched master card 10. This master card is supported in a carriage 8 which is secured to the carriage 6 and therefore moves therewith.

5 The punches 5 may also be operated under the control of electrical circuits illustrated in Fig. 9, which circuits are set up under the control of the selector keys 1 in a manner to be described later.

10 It was stated above that the leftward movement of the picker knife 2 (Fig. 4) occasions a movement to the right of the card carriage 6. This movement is effected by the following described mechanism:

15 Secured to the picker knife 2 is a bracket 11 formed as shown in Figure 3 and having one of its ends secured to a rod 13 slidably mounted in a tube 12 suitably supported on the base of the machine. The bracket 11 projects through a longitudinal slot in the tube 12. Near its left-hand end (Fig. 5) the rod 13 is provided with a rack portion 18 meshing with a pinion 15 secured to a shaft 17 upon which shaft is mounted the usual coil spring for returning the rod 13 and picker knife 2 to their normal right-hand position, as is fully disclosed in the patent to Lee and Daly No. 1,976,618.

20 A gear 16, also meshing with the rack portion 18 of rod 13, is mounted on a shaft 23 and has fixed thereto a clutch comprising a member 19 provided with a single tooth 20 laying in the plane of a pawl 21 pivotally carried on an arm 22 fixed on shaft 23. Secured on the opposite end of the shaft 23 is a gear 24 (Figs. 2 and 6) meshing with 25 teeth on the lower edge of a rack 25 forming a part of the card carriage 6.

25 For the purpose of controlling the clutch 20—21 a cam 26 pivoted at 27 (Fig. 5) is provided with a face 28 co-operating with a pin 29 projecting from the tail of pawl 21. When the rod 13 and the picker knife 2 are in their extreme right-hand positions a block 30 secured to the left-hand end of rod 13 strikes a pin 31 projecting from the cam 26 rocking said cam clockwise to disengage 30 the pawl 21 from the tooth 20 of the member 19.

35 A motor 157 mounted on the under-side of the machine base provides the power to feed the card from beneath the plate 7 (Fig. 1) to the carriage 6, and to return the carriage 6 and master card carriage 8 to their normal starting positions. The motor 157 through a clutch connection 158 (Fig. 6) drives a worm gear 159 meshing with a gear 160 fast on a shaft 161. Also secured to the shaft 161 is a clutch element 162 (Fig. 5) adjacent 40 a gear 163 meshing with teeth on the under-side of rod 13.

45 A disk 164 secured to the gear 163 has pivoted thereon at 165 an arm 166 having a tooth 167 adapted to cooperate with the clutch element 162. A link 169 connects the free end of the arm 166 to a toggle plate 168 pivoted at 170 on the disk 164. The free end of the toggle plate 168 is connected at 171 to a rod 172 slidably mounted in a pin 174 rotatably mounted on the disk 164. A spring 173 urges the toggle plate in a counter-clockwise direction about its pivot 170. The construction of the parts first described is such that the spring 173 holds the tooth 167 either in or out of engagement with the clutch element 162.

50 In order to effect a clutching action between the shaft 161 and the gear there is provided a magnet 175 (Figs. 5, 6 and 9) which, when energized in a manner to be later described, rocks its armature 176 and an arm 177 secured thereto 55 clockwise. At this movement the arm 177 engages

a pin 178 in the clutch arm 166 and engages the tooth 167 with the clutch element 162. When the motor 157 is now energized, in a manner fully set forth later, the gear 163 is driven through substantially one counter-clockwise rotation.

5 The rotation of the gear 163 shifts the rod 13 to its extreme left-ward position carrying the picker knife 2 (Fig. 4) therewith to feed the previously inserted card to the carriage 6, which has, by the clockwise rotation of gear 16, shaft 23 (Fig. 5) and gear 24 (Figs. 2 and 6), been moved to its extreme right-hand position to receive the card.

10 Near the end of the counter-clockwise rotation of the gear 163 a tail 179 on the clutch arm 166 strikes a projection 180 on a plate 181 suitably secured to the machine to effect disengagement of the tooth 167 from the clutch 162. Upon disengagement of the clutch 162—166 the rod 13 is free to return toward the right to its normal position under the influence of a coil spring attached to the shaft 17 as is fully disclosed in Patent No. 1,772,186.

15 The carriage 6 is now shifted step by step toward the left to carry the card 3 column by column past the punches 5 (Fig. 6), there being a supplemental coil spring provided to effect this movement under the control of a well-known escapement mechanism.

20 This escapement mechanism is of the type disclosed in the patent to C. D. Lake et al. No. 1,914,263 granted June 13, 1933, to which reference may be had for a full understanding of this mechanism.

25 The trip magnet 175 (Figs. 6 and 9) is energized in the following manner: At the end of the leftward movement of the carriage 6, that is, just after the last column of the card has been punched, a projection 192 (Fig. 8) secured to the carriage rack 25 strikes and rocks counter-clockwise a lever 193 pivoted on a fixed part of the machine. This movement of the lever 193 opens contacts 191 and closes contacts 194. Opening of contacts 191 disengages a brush magnet 83 (Figs. 7 and 9) permitting contacts 198 to close. At 30 this point, if the operator has placed a new card under the plate 7 (Figs. 3 and 4), contacts 195 (Figs. 6 and 9) are closed and a circuit is established from line 52, contacts 194, contacts 201 and 195, magnet 175, contacts 198 to line 55. Thus energized the magnet 175 engages the clutch 162—166 (Fig. 5). In addition to engaging this clutch the armature 176 also operates an arm 185 (Fig. 6) attached thereto. This arm opens contacts 136 and closes contacts 190.

35 Opening the contacts 136 opens the circuits to the brush magnet 83, and to the punch magnet 49 making it impossible to operate these devices while the carriage is being returned.

40 Closing contacts 190 establishes a circuit from line 52, contacts 190, motor 157, contacts 198 to line 55. The motor 157 now drives the gear 163 to feed the newly inserted card 3, and returns the carriage 6 to receive said card.

45 The contacts 136 are held open and the contacts 190 are held closed by a latch 187, an ear 188 (Fig. 6) of which is adapted to be struck by a bent plate 189 (Fig. 5) secured to the gear 163 near the end of its rotation. When this occurs the contacts 136 again close and contacts 190 open stopping the motor 157.

50 It may be observed that until the operator places a card under the plate 7 and closes this plate the contacts 195 remain open, maintaining the circuit through the trip magnet 175 open,

which makes it impossible to operate the machine after the last column has been punched until a new card is inserted and the plate 7 closed.

The plate 7 (Figs. 3 and 4) is opened automatically on the return stroke of the picker knife 2 in the following manner:

A latch 110 pivotally supported on the under side of the plate 4 is urged by a spring 111 into cooperative relation with a projection 112 on the plate 7 to hold this plate latched in its closed position. A bypass pawl 113 pivotally supported by a bracket 114 secured to the plate 4 extends downwardly into the path of the bracket 11.

When the bracket 11 travels toward the left (Fig. 4) it wipes by the pawl 113 without affecting the latch 110. On its return stroke, toward the right, the bracket 11 strikes the pawl 113 which being in contact with an ear 115 of the latch 110 rocks said latch counterclockwise (Fig. 4) to release the plate 7 which is immediately raised by a spring 116.

The punches 5 are normally held in their raised position by individual coil springs 38. Interposers 39 (Fig. 6) supported at their right-hand ends on a cross-member 40, rest on the upper ends of the punches 5. A plate 41 prevents further upward movement of the interposers 39 and consequently of the punches 5.

Depression of a key 9 rocks a bell crank 45 counter-clockwise, which, through a pin and slot connection 47, slides the corresponding interposer 39 toward the left to bring the interposer beneath a projection 44 on an actuator plate 42 so that upon depression of said actuator plate, the selected interposer 39 and consequently the corresponding punch 5 will be depressed.

In order to operate the punches a magnet 49 (Fig. 5) is provided which when energized attracts its armature 50 and through a link 53 rocks a bell crank 54 counter-clockwise. The bell crank by a link 56 rocks the actuator plate 42 downwardly to operate the selected punch 5.

The magnet 49 is energized upon depression of a key 9 as follows: Leftward movement of any one of the interposers 39 rocks a bail counter-clockwise raising a link 91 closing contacts 95. These contacts 95 are in series with the punch magnet 49 (see circuit diagram Fig. 9) and upon their closure a circuit is established from line 52, contacts 136, contacts 95, punch magnet 49, magnet 47, wire 48 to line 55, thus energizing the punch magnet 49 whenever a key 9 is depressed.

When the punch magnet 49 operates its armature 50, a projection 92 on the link 53 rocks the link 91 to permit the contacts 95 to open.

Each time a key 9 is depressed an escape mechanism is operated under the control of the bail 98 to permit the carriage to escape to the next column.

After the last column has been punched the carriage closes contacts 194 as above described. In addition to the function set forth above, these contacts also cause the energization of a magnet 199 (Fig. 9) which controls the operation of an automatic card ejecting mechanism. This mechanism is disclosed in the patent to J. M. Cunningham, No. 1,916,965, granted July 4, 1933, to which reference may be had for a complete understanding of the construction and operation of the card ejector device.

The magnet 199 (Fig. 9) closes contacts 201 in the trip magnet circuit to complete the circuit through the trip magnet 175.

The keys 9 may be operated by selector magnets 60 under the control of a pattern or mas-

ter card 10 in a well-known manner. The master card is carried in a carriage 8 and is sensed as it passes between sensing brushes 68 (Fig. 7) and a contact roll 69 concomitantly with the leftward passage of the card 3 past the punches 5.

When the last column in the new card 3 (Figs. 1 and 2) has been punched and the carriages 6 and 8 are to be returned toward the right (Fig. 7) it is necessary to drop the brushes 68 out of contact with the card 10 in order to prevent damage to the card and brushes. This is accomplished by de-energizing the brush magnet 83.

It will be recalled that just after the last column is punched the contacts 191 (Figs. 8 and 9) are opened by the lever 193 (Fig. 8). These contacts are in series with the brush magnet 83, thus de-energizing this magnet when the card carriage is in the last column position which is to the extreme left (Fig. 7). De-energization of the magnet 83 allows its armature 80 (Fig. 7) to rock counter-clockwise thrusting the link 71 toward the right and rocking the arm 78 clockwise thus lowering the brushes 68. As soon as the carriage commences its movement toward the right the contacts 191 close, but the brush magnet circuit 15 it held open at the contacts 136 (see Figs. 6 and 9), until the carriage arrives at its extreme right-hand position. At this point the latch 187 (Fig. 6) is tripped permitting contacts 136 to close energizing the brush magnet 83 (Fig. 7) 30 which raises the brushes 68 into contact with the card.

The contacts 87 are open when there is no master card in the master card carriage. These contacts are in the brush magnet circuit holding this 35 magnet de-energized until a card is placed in the carriage and the door 84 closed pressing the plunger 86 downwardly to close the contacts 87. A latch 85 holds the door closed until released manually.

When a master card is being sensed and the punches operated under the control of the pattern of the master card the circuit through the selector magnets 60 is traced as follows with reference to Figure 9: Line 52, contacts 136, manual switch 88 closed when duplicating from a master card, cam operated contacts 89 (described later), wire 90, common brush 74, contact roll 69, brush 68 through hole in card, corresponding selector magnet 60 to line 55. The magnet 60 50 operates a lever 61 which in turn operates the corresponding numeral key 9 causing the punch to function in the manner set forth above.

The above briefly described punching device effects punching of data common to all cards 55 under the control of a pattern card and also effects punching of data which varies with each individual card under the control of manually operable keys.

The punch selector magnets 60 (Fig. 9) may 60 also be selected under the control of the rate extension keys 1 (Figs. 1, 10, 11, 12 and 14). Depression of one of these keys selects a plurality of columnar circuits. The circuits are then sensed column by column by means of a read-out 65 strip 228 (Figs. 1, 2 and 9).

The selector mechanism is carried in a framework comprising a base 202 (Figs. 10, 11, 12 and 14), side frames 203 and 204 secured to the base and formed at the top by cross members 205, 206 and 207. The entire mechanism is enclosed in a casing 208 on top of which is supported a keyboard in which are mounted the rate extension keys 1.

The keys 1 are slidably mounted in a bottom 75

- plate 209 (Figs. 11, 12 and 14) and a top plate 210, the latter plate being supported on cross-bars 211 extending between the side frames. Associated with each of the keys 1 is a bell crank 212, which bell cranks are pivotally mounted on rods 213 set into cross-bars 214 extending between the side frames. The downwardly extending arms of the bell cranks 212 are embraced by notches in the upper edges of slides 215 supported on rods 216 and 217. These rods are supported in cross-bars 205 and 207 respectively.
- By referring to Figure 14 it can be seen that depression of a key 1 acting through the associated bell crank 212 moves the corresponding slide 215 toward the left. At this movement of the slide a projection 218 on the right-hand end thereof wipes by the end of a spring pressed detent bar 219 supported between a pair of arms 220. As soon as the projections 218 have passed the end of detent 219 a spring 21 restores the detent to its normal position, thus holding the slide 215 in its moved position as indicated in Figure 14. In this condition the operated key 1 is held in its depressed position until released later in the operation by mechanism later to be described.
- The usual ball interlock 222 is provided to prevent depression of more than one key 1 at a time.
- The arms 220 supporting the detent bar 219 are pivotally mounted on a rod 223 mounted in brackets 224 secured to the under side of a plate 225 extending between the side frames. When the detent bar 219 is rocked counter-clockwise to release the slide 215 a spring 221 restores said slide toward the right to its normal position.
- Each of the keys 1 controls a value plate 232 upon which are mounted a plurality of digital value bars 233 (see Figs. 14, 19 and 20). The plates 232 are mounted in a frame or tray comprising side members 234 and 235 (Fig. 14) formed at their ends by members 236 and 237 (see also Fig. 21). The tray is conveniently removable from the machine for the purpose of changing the value plates 232 or another tray wherein the plates 232 have different values assembled thereon may be inserted. The tray rests on bars 238 and 239 secured on frames 240 and 241 mounted on the base 202 and extending longitudinally of the machine.
- Referring now to Figure 12 the value plates are normally held in their raised positions by pairs of segments 242 and 243 pivoted on rods supported in a cross-bar 244. Each of the slides 215 is provided with a hook projection normally in engagement with the end of one arm 246 of the segment 242. Projections 247 on the value plates rest on arms 248 of the segments 242 and 243, thus holding the value plates in their raised positions.
- When a key 1 is depressed it shifts its slide 215 toward the left releasing the arm 246 and segment 242 to the action of spring 231 which immediately rocks the segment 242 counter-clockwise. Due to the segment 242 meshing with segment 243 the latter segment is rocked clockwise. This movement of segments 242 and 243 lowers the value plate 232 and brings the rounded end of an arm 249 of the segment 243 beneath the upper wall of a channel member 250. The member 250 is then lowered (by mechanism presently to be described) further rocking the segments 242 and 243 which press the value plate downwardly the full extent of its movement in which position the parts are shown in Figure 14. In this position of the plate 232 it may be seen that each of the value bars 233 has depressed an associated bar 251 a distance commensurate with the digital value, represented by the length of the associated value bar 233.
- Each of the bars 251 (Fig. 11) is pivotally mounted on one arm of each of three bell cranks 252 and on one arm of bell crank 253. These bell cranks are pivoted on rods 254 mounted on brackets 255 bent upwardly from the bars 238 and 239 (Fig. 14). In Figure 12 all of the bars 251 are shown, but in Figure 14 only a few of these bars are fully shown, the remainder being omitted for the sake of clearness.
- The other arms of the bell cranks 252 and 253 are connected together by a link 256. This arrangement of the parts insures that the bar 251 will receive a parallel movement regardless of the value plate 232 depressed, that is, if a plate 232 is depressed at either end or in the center of the bar 251.
- The lower arm of bell crank 253 carries a block of insulating material 257 (see Fig. 14), upon which is mounted a pair of brushes 258 and 259 electrically connected together. These brushes straddle a contact segment 260 on one side of which is mounted a plurality of spaced contacts 261 representing the digits 0 to 9 inclusive. A common contact strip 262 is mounted on the other side of the segment 260.
- Thus it can be seen that when a value bar 233 (Fig. 14) whose length represents the digit 9, operates the bar 251 (Fig. 11), the bell crank 253 will be rocked counter-clockwise to bring the brush 258 into contact with the "9" contact 261. A spring pressed aliner 263 carried by an arm 264 pivotally carried by a projection 265 of bell crank 253 serves to align the brush 258 with the particular contact 261 to which it has been moved.
- The contacts 261 are wired through a cable 226 (Fig. 1) to a plugboard 227 (Fig. 2) where they are plugged to a read-out strip 228 which will be fully described later in connection with the circuit diagram.
- The illustrative embodiment of the instant invention discloses that twenty-two value bars 233 may be assembled on each value plate 232 (Fig. 19), representing an equal number of columns to be punched on the card. Each of these bars 233 controls or operates a bar 251 to set the corresponding contacts 258 there being a commutator 260 for each of the value bars 233. It is to be understood that the value plates 232 may be extended to include any desirable number of value bars 233 without departing from the spirit of the invention.
- The value bars 233 are removably assembled on the plate 232 by inserting the end of the bar under the comb 266 of a spring clip 267, engaging a notch 268 in the end of the bar with a projection 269 on the plate 232 and then engaging a notch 270 in the side of the bar with a projection 271 on the lower edge of the plate 232 (see Figs. 19 and 20). Thus a bar 233 of any digital value or length may be assembled in any columnar position on the plate 232. The set-up may be quickly and easily changed at will.
- The mechanism for lowering the selected value plate 232 includes a motor 277 (Figs. 12 and 16) mounted on the base 202 of the machine. By means of worm gears (not shown) the motor drives a shaft 278 (Figs. 16 and 18) journaled in brackets 279 and 280 secured to the base 202. A gear 281 free on the shaft 278 and driven through a clutch meshes with a gear 282 pinned on a shaft 283 also journaled in frames 279 and 280.

Also pinned on the shaft 283 is a pair of cams 284 and 285 (Fig. 18) co-operating with rollers 286 carried by a cam arm 287 pinned to a shaft 288 to which shaft is also fast a lever 289. One 5 end of the lever 289 forms a segment 290 which meshes with a segment 291 on one arm of a lever 292 pivotally supported at 293 on the bracket 279.

The ends of the levers 289 and 292 opposite the segments 290 and 291 are bifurcated and embrace studs 294 projecting from rods 295 mounted 10 to slide vertically in brackets 296 secured to frames 203 and 204. Also securely mounted on the rods 295 are blocks 297 which pivotally carry arms 298 to which arms are secured the channel 15 bar 250 (see also Fig. 14).

As viewed in Figures 12 and 16, the motor 277 when energized as set forth below, rotates the shaft 283 and cams 284—285 in a clockwise direction which movement rocks the cam arm 287, shaft 288 and the lever 289 clockwise. Due to the meshing of segments 290 and 291 this rocks the lever 292 counter-clockwise. By examination of Figure 16 it may be seen that clockwise movement of lever 289 and counter-clockwise movement of lever 292 slides the rods 295 downwardly equidistantly. At this movement the arm 249 of the selected segment 243 (Fig. 12) which assumed a position beneath the upper wall of the channel bar 250 is rocked further clockwise rocking the segment 242 further counter-clockwise lowering the associated value plate 232 to the position in which it is shown in Figure 14, thus setting each of the circuit selecting brushes 258—259 for which there is a value bar 233 assembled 35 in the value plate 232.

The gears 281 and 282 and the cams 284—285 are driven through a clutch which effects one-half of one complete rotation of the cams 284—285. The clutch is then disengaged holding the channel bar 250 in its lower position to permit reading out and punching the values represented by the circuits selected through brushes 258—259. After the last circuit or column has been punched the clutch is again operated to drive the cams 284—45 285 another half rotation thus completing a full rotation of the cams and raising the channel bar 250 to restore the depressed value plate 232 and to release the depressed key 1.

The clutch is described as follows: A disc 299 fast on the shaft 278 has a notch in its periphery adapted to be engaged by a clutch pawl 300 pivotally carried by an arm 301 free on the shaft 278 but secured to the gear 281. A spring 302 urges the pawl 300 into engagement with the notch on disc 299 but is normally restrained and the pawl held in ineffective position by the armature 303 of a pair of clutch magnets 304. At the proper time (as fully set forth later in the circuit description) the magnets 304 are energized attracting the armature 303 and permitting the spring 302 to engage the clutch pawl. The gear 281 then receives one complete rotation being arrested by the armature at the end of said rotation. The ratio of the gears 281 and 282 being two to one the latter gear receives but one-half rotation to lower the selected value plate 232. After the last column represented on the value plate has been punched the magnets 304 are again energized thus engaging the clutch which effects the second half of the rotation of gear 282 and cams 284—285 to restore the depressed value plate.

Referring now to Figures 12 and 14, the lower wall of the channel bar 250 on its upward movement picks up the arm 249 of segment 243 rock-

ing this segment counter-clockwise thus rocking the segment 242 clockwise slightly past normal position so that the arm 246 is in position to be engaged by the projection 245 on the slide 215. At about this time screw heads 305 (see also 5 Fig. 16), on the arms 298 strike projection 306 on the detent bar 219 rocking said bar counter-clockwise. This frees the slide 215 to its spring 231 which immediately restores the slide toward the right to its normal position and raises the depressed key 1 to its undepressed position. As the slide 215 moves to the right the projection 245 assumes its position beneath the end of the arm 246 thus retaining the segments 242 and 243 10 in their raised positions.

The circuit selecting brushes 258—259, bell cranks 252—253 and the bars 251 (Fig. 11) are positively restored by a restoring bail 307 carried by arms 308 pivotally mounted on a stud 309 projecting inwardly from the frames 240 and 241. 15 The bail 307 is operated by a stud 310 carried near the lower end of one of the rods 295 (see also Fig. 12), which stud, as the rod 295 moves upwardly on its restoring movement, engages and rocks counter-clockwise an arm 311 connected to one 20 arm 308 by a bail 312. Movement of the stud 310 is therefore transmitted to the bail 307 rocking said bail counter-clockwise against the ends of the links 256 to restore these links and their 25 associated mechanism from their several selected 30 positions to their normal position as shown in Figure 11.

Referring to Figures 14 and 16 it may be observed that tails 313 on the arms 298 are held against the lower side of blocks 297 by springs 314. 35 The purpose of this construction is to eliminate the possibility of breakage or damage in the event a value plate 232 sticking. Should this occur the channel bar 250 and its supporting arms 298 would be cammed clockwise against the tension of springs 314 without damaging any of the parts.

Referring now to Figure 9 a description will be given of the circuit diagram pertaining to the operation of the rate extension part of the device, the punch circuit having been described above. 45

It was set forth above how depression of a key 1 (Fig. 14) shifts its slide 215 toward the left. Pivotally mounted on a rod 315 supported in brackets 316 secured to the cross-bar 205, is a bail 317 having its upper edge in the paths of 50 all of the slides 215. A projection 318 (see also Fig. 10), of the bail 317 carries an insulating disc 319. As viewed in Figure 14 leftward movement of the slide 215, by the depression of a key 1, rocks bail 317 counter-clockwise closing a pair of contacts 320 establishing a circuit from line 52, contacts 321, contacts 320, contacts 322, clutch magnets 304, wire 48 to line 55. Energization of the clutch magnets 304 attracts armature 303 (Fig. 16) permitting spring 302 to engage clutch 60 pawl 300 with clutch disc 299. At the same time closure of contacts 320 energizes the drive motor 277 the circuit extending from line 52, contacts 321, contacts 320, wire 323, motor 277, wire 324 to line 55. The motor 277 now rotates the disc 65 299 through one complete rotation, which, as set forth above, rotates cams 284—285 one-half rotation to lower the channel bar and there-through the selected value plate.

Shortly after the beginning of the rotation of 70 the cams 284—285 the contacts 322 (Fig. 9) are opened and a pair of contacts 351 are closed by a cam 326 (see also Fig. 12), fast on the shaft 283. The opening of contacts causes deenergiza-

tion of the clutch magnet 304 so that upon completion of one revolution the tail of the clutch pawl 300 strikes the armature 303 disengaging the clutch. This lowers the selected value plate 5 232 which sets the selector brushes 258-259 according to the value bars 238 on the particular value plate and holds this setting until the clutch magnet 304 is again energized. While the selectors are thus set the card carriage advances step by step sensing from the commutator strip 228 the values to be punched in each column.

When the card carriage advances to the last columnar position represented on the selected value plate the clutch magnet 304 is again energized and the cams 284-285 restore the value plate to its normal raised position. This energization of the clutch magnet is effected as follows: A plughub 327 (Fig. 9) is connected by a plugwire 328 to a plughub 329 which is connected 10 to the contact 330 representing the last column to be punched under the control of the preset device. There is a contact 330 for each card column. A three tined brush 331 (see also Figs. 1 and 2), mounted on the card carriage and moving therewith wipes over the contacts 338 and over a common conductor 332. As the card carriage advances to the last column a circuit is established from line 52 over contacts 136, through switch 88 contacts 89 now closed, wire 25 333, cam contacts 334 closed when the selected value plate reached its lowermost position by cam 335 (Fig. 12), common conductor 332, brush 331, last column contact 330, plugwire 328, a relay magnet 336 to line 55. This energizes the 30 relay magnet 336 which closes contacts 337 and contacts 338. The contacts 337 are connected to a plughub 339 which is connected by a plugwire 340 to a plughub 341. The plughub 341 is connected to the common conductor 262 on the commutators 260 (see Fig. 11), associated with the 40 last column.

Closure of contacts 337 establishes a circuit from line 52 over the circuit first described including the plughub 327, then over contacts 337, 45 plugwire 340, common conductor 262 of the last column commutator 260, the selected digital contact 261, corresponding punch selector magnet 60 to the line 55. Energization of the selector magnet 60 as set forth above closes contacts 65 (Figs. 5 and 9) energizing the punch magnets 49 to operate the selected punch. At the same time the punch magnets 49 are energized a magnet 47 in the punch magnet circuit is energized closing its contacts 342. When these contacts 50 are closed a circuit is established from line 52, wire 343, contacts 338, contacts 342, a relay magnet 344 to line 55.

Closing contacts 346 energizes the clutch magnet 304 over the following circuit: Line 52, contacts 346, contacts 351 which were closed as contacts 322 were opened shortly after beginning of the downward movement of the value plate lowering mechanism, clutch magnet 304, wire 48 to line 55. This trips the clutch and the mechanism operates to restore the value plate to its normal raised position.

Since the circuit through the punch magnets 49 and the magnet 47 is established momentarily it is necessary to provide a holding circuit for the contacts 346. This is effected by closure of contacts 345 which establishes a holding circuit from line 52, contacts 321, contacts 320, wire 352, contacts 345, relay magnet 344 to line 55. This 70 circuit holds the magnet 344 energized and the

contacts 346 closed for a sufficient period to permit energization of the clutch magnet 304.

As soon as the value plate starts its restoring movement the cam 335 opens contacts 334 opening the circuit to the common conductor 332 of the read-out commutator 228. At approximately the same time the cam 326 opens contacts 351 and closes contacts 322 so that after the value plate is fully restored and the previously depressed key released, depression of another key 11 will immediately energize the clutch magnet to lower the selected value plate as above described.

As set forth above the tray or magazine carrying all of the value plates is removable for the purpose of changing the value plates. It is desirable to prevent depression of a key 1 and/or operation of the machine while the tray is removed and until the tray is in its proper position. In this end an interlock now to be described is provided. This interlock is best disclosed in Figures 10 and 21, and includes an arm 353 secured on one end of a shaft 354 extending the length of the tray and journaled in the end plates 236 and 237 thereof.

The free end of the arm carries a spring pressed latching plunger 355 adapted to cooperate with a hole 356 in the end plate 236 to latch the arm in the position shown in Figure 22. With the arm 353 in the position shown in Fig. 21 the tray is free to be removed from the machine. When the tray is in its proper position in the machine the operator pulls out the plunger 355 and rotates the arm approximately ninety degrees in a counter-clockwise direction (Fig. 21). In this position a bracket 357 secured on the inside of the frame 203 (see Fig. 10), lies in the path of a projection 358 on the hub of the arm 353 thus preventing removal of the tray until the arm is rotated clockwise.

The arm 353 carries a disc 359 of insulating material, which, when the arm is in its down or locking position closes contacts 321 (see Fig. 9), making possible the closure of the circuits to the clutch magnets 304 and the motor 277 as described above. When the arm 353 occupies the position shown in Figure 21, in which position the tray is free to be removed these circuits are opened at the contacts 321 so that the clutch magnet and motor may not be energized.

The contacts 321 also control the energization of a key lock magnet 360 (Figs. 9 and 10). When the tray is in position and the disc 359 is in the position indicated at 359' the contacts 321 are closed and the magnet energized over a circuit extending from the line 52 (Fig. 9), contacts 321, wire 361, magnet 360 to line 55. Energization of the magnet 360 attracts its armature 362 rocking counter-clockwise an arm 363 integral with the armature. This removes the free end of arm 363 from the path of a projection 364 of the bail 317 permitting depression of a key 1.

When the arm 353 is rocked clockwise to permit removal of the tray the contacts 321 open de-energizing the magnet 360, whereupon a spring 365 rocks the armature 362 and the arm 363 clockwise bringing the free end of the latter into the path of the projection 364, thus preventing depression of a key.

If it is desired to punch an "X" in addition to a digital in the same column a plugwire 370 (Fig. 9) is plugged from a plughub 371 to the desired columnar plughub 329. When the brush 331 escapes to the column to which the plugwire 370 is connected a circuit is set-up from line 52, contacts 136, switch 88, contacts 89, wire 333, cam 75

contacts 334, common strip 332, brush 331, selected contact 330, plughub 329, plugwire 370, a magnet 372 to line 55. Energization of magnet 372 closes contacts 373 and 374. One side of the contacts 373 and 374 are connected by a wire 375 to line 52 and the other side of contacts 373 is connected by a plugwire 376 to an "X" plughub which is wired to the "X" punch selector magnet 60. The other side of contacts 374 is connected by a plugwire 377 to the desired preset plughub 341. The "X" magnet 60 and the digital magnet 60 corresponding to the selected preset positions will be simultaneously energized to select their corresponding punches for operation to punch an "X" hole and a digital hole in one column.

Referring now to Figure 25 which represents a typical plugging arrangement in the plughubs 341 are connected to the common strip 262 on the selector commutator and the plughubs 329 are connected to the columnar contacts 330 (see also Fig. 9). The plugging from the commutator position 341 to the columnar position 329 is made through a multi-contact relay 378 (Fig. 9). The purpose of this relay is to change the values to certain columns under the control of a special key 379 (Figs. 10 and 11). There are three of these special keys 379 provided in the machine but it is believed necessary to describe but one. Depression of the key 379 by means of its slide 215 closes contacts 380 (Figs. 9 and 10) which causes energization of the magnet 378. This shifts contacts 381 (Fig. 9) opening the upper contact and closing the lower contacts. With the key 379 undepressed and the magnet 378 de-energized the upper contacts 381 are closed.

It is to be remembered that the tray carries 100 value plates 232 each having different value bars assembled thereon representing the rates of electrical consumption. Fig. 24 shows a list of such rates. For example, if the key 1 representing rate 44 is depressed, the selected value plate will have assembled thereon value bars representing the data pertinent to this rate and which is to be punched in columns 52 to 75 inclusive of the card (Fig. 23).

Taking as an example the value plate for rate 44, the values of the bars from left to right are as follows:

Pos.	Value	Pos.	Value	Pos.	Value
1	0	10	8	18	6
2	4	11	4	19	0
3	4	12	2	20	7
4	2	13	5	21	9
5	1	14	6	22	7
6	0	15	0		
7	0	16	8		
8	0	17	8		
9	2				

These values are set on the commutators 260 when rate key 44 is depressed. Other values are plugged directly from digital plughubs 385 (Figs. 9 and 25) and from group plugs 386 to certain of the columnar plugs 329.

Let it now be assumed that rate key 44 has been depressed and that no special key 379 has been depressed, in which case all of the contacts 381 of the multi-contact relay will be in their upper or normal position. As the carriage escapes to column 52 and the brush 331 (Fig. 9) makes contact with columnar contact 330 for column 52 a "0" will be punched in this column since it is plugged to the group plugs 386 which are plugged to the "0" digit position 385, thus energizing the "0" punch selector magnet 60. The carriage now

escapes to column 53 which is plugged to the "X" punch selector magnet so that "X" will be punched in column 53. Column 54 is plugged through the upper contacts 381 to position 1 on the value plate which contains a "0". Columns 55 and 56 are plugged directly to positions 2 and 3 respectively on the value plate and punch "4's" in these columns. Columns 52 to 56 inclusive now have 0X044 punched therein representing the rate or consumption. Columns 57 and 58 represent the billing period and are plugged to the "2" digit position and to the group plug or "0" respectively punching "2" and "0" in these columns. Column 59 is plugged through upper contacts 381 to the 8 position on the value plate whose commutator 260 is set at "0". Column 60 is plugged to the "0" group plugs 386. Column 61 is plugged through the upper points of a relay 387 to the "2" digital position 385. Column 62 is plugged through the upper points of relay 387 to the "0" group position 386. Columns 59 to 62 inclusive now have punched therein 0020 representing the base rate. Columns 63 to 65 inclusive representing a control field column 63 being plugged through upper contacts 381 to the "0" group plugs. Columns 64 and 65 are plugged through the upper points 381 to positions 6 and 7 respectively which contain a "0" in both cases. Thus 000 will be punched in these columns. Columns 66 to 70 inclusive represent the amount of the gross bill. Column 66 is plugged directly to the 0 group plugs. Column 67 is plugged through the multi-contact relay to the "0" group plugs. Column 68 is plugged through the relay to position 9 on the value plate which contains a "2". Column 69 is plugged through the relay to position 10 which contains an "8". Column 70 is plugged through the relay to position 11 in which there is a value "4". Columns 66 to 70 inclusive will therefore have 00284 punched therein. Column 71 is plugged directly to the "0" group plugs 386. Column 72 is plugged through the relay to the "0" group plug. Column 73 is plugged through the relay to the 12 position on the value plate wherein there is a "2". Column 74 is plugged through the relay to position 13 containing the value "5". Column 75 is plugged through the relay to position 14 having a "6" therein. Thus 00256 is punched in columns 71 to 75 inclusive representing the net bill.

The remaining columns of the card are punched from the master card, manually punched or prepunched as follows: Columns 1 to 8 inclusive are punched from data on the master card. Columns 9 to 38 inclusive are pre-punched. Columns 39 to 41 inclusive are duplicated from the master card. Columns 42 to 46 are pre-punched. Columns 47 to 51 are manually punched. Columns 52 to 75 are punched under the control of the selected rate key and columns 76 to 80 are manually punched.

Three special keys 379 (Figs. 1 and 10) are provided, only one of which is herein described since they all serve the same purpose, that is, to operate the multi-contact relays to change the values selected from the value plates.

If we now depress rate key 44 and in addition depress key 379 labeled R1 all of the contacts 381 on the multi-contact relay 378 are shifted opening the upper contacts and closing the lower contacts. This opens all the circuits plugged through the upper contacts and closes those circuits plugged through the lower contacts causing the following values to be read out of the value plate and punched: Columns 52 and 75

53 will punch the same data since they are plugged directly to the "0" and "X" plugs. By depressing the R1 key in connection with the 44 rate key the consumption is changed from 5 44 to 244. It is necessary therefore to punch a "2" in column 54 instead of the "0". This column is plugged through the lower points of the relay to value plate position 4 which contains a "2" which value will therefore be punched in 10 column 54. Columns 55 and 56 are plugged directly to value plate positions 2 and 3 and as before "4" will be read out and punched in columns 55 and 56, thus punching 0X244 in columns 52 to 56 inclusive representing the rate 15 or consumption. Columns 57 and 58 will be punched the same as previously since they are plugged directly to the "2" and "0" positions. Column 59 is plugged through the lower contacts to the "0" group plugs. Column 60 is 20 plugged directly to the "0" group plug. Columns 61 and 62 remain the same since these columns are plugged through relay 387 which is not operated when the R1 key is depressed. Column 63 is plugged through the lower points of the 25 relay to the 5 value plate position which contains a "1". Columns 64 and 65 are plugged through lower contacts to value plate positions 2 and 3 having the values "4" set therein. This punches 144 in columns 63 to 65 inclusive on 30 the card. Column 66 is plugged directly to the "0" group plug. Columns 67, 68, 69 and 70 are plugged through the lower contacts to value plate positions 15, 16, 17 and 18 respectively, thus causing 00886 to be punched in columns 35 66 to 70 inclusive representing the gross bill. Column 71 is plugged directly to the "0" group plugs. Columns 72, 73, 74 and 75 are plugged through lower contacts to value plate positions 19, 20, 21 and 22 respectively, thus punching 00797 in these columns representing the net bill.

The plugboard appearing in Figure 2 is shown diagrammatically in Figure 25. It is obvious that the data punched under the control of the value plates selected by keys 1 may be plugged 45 to and punched in any group of columns on the card, the above described plugging being a typical arrangement for residential rates. When it is desired to punch commercial rates, illustrated in the right-hand half of Figure 24, the tray 50 carrying the value plates for the residential rates is removed from the machine and another tray inserted which carries value plates for commercial rates.

One hundred rate keys 1 are provided in the 55 machine. By the use of the special keys 379 labeled R1, R2, and R3 which control the multi-contact relays 378, 387 and 388 (Fig. 9) the values read out from the value plates may be split and extended three ways. Thus, in effect 60 the one hundred rate keys 1, in combination with one of the keys 379 control the selection of three hundred rates.

While there has been shown and described and 65 pointed out the fundamental novel features of the invention as applied to a single modification, it will be understood that various omissions and substitutions and changes in the form and details of the device illustrated and in its operation may be made by those skilled in the art 70 without departing from the spirit of the invention. It is the intention therefore to be limited only as indicated by the scope of the following claims.

What is claimed is:

75 1. In a perforating machine, the combination

of a plurality of punches, selector magnets for said punches, a series of columnar contacts, a series of selector circuits, differentially adjustable means in said circuits intermediate the magnets and the contacts, and means controlled by a single manipulative means to simultaneously adjust a plurality of said differentially adjustable means simultaneously to connect a plurality of the magnets to predetermined columnar contacts.

2. In a perforating machine, the combination of a plurality of punches, selector magnets for said punches, a series of columnar contacts, a series of selector circuits, commutator elements in said circuits intermediate the magnets and the contacts, and means controlled by a single manipulative means to operate a plurality of said commutator elements simultaneously to connect a plurality of the magnets to predetermined columnar contacts.

3. In a perforating machine, the combination of a plurality of punches, selector magnets for said punches, a series of columnar contacts, a series of selector circuits, commutator elements in said circuits intermediate the magnets and the contacts, means controlled by a single manipulative means to operate a plurality of said commutator elements simultaneously to connect a plurality of the magnets to predetermined columnar contacts, and means successively to render the circuits effective to energize the magnets.

4. In a perforating machine, the combination of a plurality of punch selector magnets, a plurality of columnar contacts, commutator elements in said circuits to selectively connect the magnets with the columnar circuits, a plurality of value members, manipulative means to select the value members, and means to operate the selected value member to simultaneously set a plurality of the commutator elements.

5. In a perforating machine, the combination of a plurality of punch selector magnets, a plurality of columnar circuits, commutator elements in said circuits to selectively connect the magnets with the columnar circuits, a plurality of value members, means to normally hold the value members in inoperative position, manipulative means to selectively release the value members, and means to operate the selected value members to simultaneously set a plurality of the commutator elements.

6. In a perforating machine, the combination of a plurality of punch selector magnets, a plurality of columnar circuits, commutator elements in said circuits to selectively connect the magnets with the columnar circuits, a plurality of value members, operating means for said value members, means to normally hold the value members in inoperative position, manipulative means, and means actuated by the manipulative means to selectively release the value members and to initiate an operation of the operating means to simultaneously set a plurality of the commutator elements.

7. In a perforating machine, the combination of a plurality of punch selector circuits, a plurality of columnar circuits, commutator elements in said circuits to selectively connect the magnets with the columnar circuits, a plurality of value members, operating means for said value members, means to normally hold the value members in inoperative positions, manipulative means, means actuated by the manipulative means to selectively release the value members and to initiate an operation of the operating means to

simultaneously set a plurality of the commutator elements, means to successively sense the columnar circuits, and means becoming effective when the last columnar circuit is sensed to initiate an operation of the operating means to restore the selected value member.

8. In a perforating machine, the combination of a plurality of punch selector magnets, a plurality of columnar circuits, selective means in said circuits to simultaneously connect a plurality of selector magnets to predetermined columnar circuits, a plurality of value members each member being provided with a plurality of value elements, manipulative means to select the value members, and means operated by each of the value elements on the selected value members to operate the selective means according to the values of the several value elements.

9. In a perforating machine, the combination of a plurality of punch selector magnets, a plurality of columnar circuits, selective means in said circuits to simultaneously connect a plurality of selector magnets to predetermined columnar circuits, a plurality of value members each member being provided with a plurality of value elements, manipulative means to select the value members, means operated by each of the value elements on the selected value member to operate the selective means according to the values of the several value elements, other manipulative means, and means controlled by said other manipulative means to change certain of the connections effected by the selective means.

10. In a perforating machine, the combination of a plurality of punches, selector magnets for said punches, a series of columnar contacts, a series of selector circuits, commutator elements in said circuits intermediate the magnets and the contacts, means controlled by a single manipulative means to operate a plurality of the commutator elements to simultaneously connect a plurality of the magnets to predetermined columnar contacts, and means controlled by other manipulative means to change certain of the connections effected by the commutator elements.

11. In a perforating machine, the combination of a plurality of punches, selector magnets for said punches, a series of columnar contacts, a series of selector circuits, commutator elements in said circuits to selectively connect the magnets to the columnar contacts, a plurality of value plates each plate being provided with a plurality of value elements there being a value element for each commutator element, means to operate the value plates, and means operated by the value elements to adjust the commutator elements according to the values of the several value elements.

12. In a perforating machine, the combination of a plurality of punch selecting magnets, a plurality of columnar circuits, a plurality of commutator elements to selectively connect the magnets to the circuits, a plurality of value members, keys to select the value members, a plurality of value elements on each of said value members, means operated by the value elements to differentially adjust the commutator elements

according to the values of the value elements, means to successively render the circuits effective to energize the magnets, means to hold the commutator elements in their adjusted positions, and means becoming effective when the last magnet is energized to restore the commutator elements.

13. In a perforating machine, the combination of a plurality of punch selector magnets, a plurality of columnar circuits, commutator elements to selectively connect the magnets to the circuits, a plurality of value members to differentially adjust the commutator elements, manipulative means to select the value members, operating mechanism for the value members, a motor to drive the operating mechanism, a clutch between the motor and the operating mechanism, means actuated by the manipulative means to engage the clutch and to energize the motor, automatic means to disengage the clutch to hold the commutator elements in adjusted positions, means to successively energize the selected magnets, means effective when the last magnet is energized to engage the clutch to restore the operating mechanism, and means effective when the operating mechanism is restored to de-energize the motor.

14. In a perforating machine, the combination of a plurality of punch selector magnets, a series of columnar circuits, commutator elements to selectively connect the magnets to the circuits, a plurality of value members, a plurality of value elements removably carried by each value member, common means to retain the value elements on the value members, manipulative means to select the value members, and means operated by the value elements to differentially adjust the commutator elements according to the values of the several value elements on the selected value members.

15. In a perforating machine, the combination with a plurality of punch selector magnets, a series of columnar circuits, and a plurality of commutator elements to selectively connect the magnets to the circuits, of a plate provided with spaced projections along its upper and lower edges, a plurality of bars representing digital values each bar being provided with notches cooperating with the projections, a retaining member cooperating with all of the bars to removably retain said bars in their positions on the plate, and means operated by the bars to adjust the commutator elements commensurate to the values represented by said bars.

16. In a perforating machine, the combination of a plurality of commutator elements, a plurality of circuits, a plate provided with spaced projections along its upper and lower edges, a plurality of interchangeable value bars each bar being provided with notches cooperating with the projections, a retaining member common to all of the bars to removably retain the bars on the plate, and means operated by the bars to simultaneously adjust a plurality of the commutator elements to select a plurality of the circuits.

CLAIR D. LAKE.
